(57) **CLAIM**

The ornamental design for a combined fan with light as shown and described.

DESCRIPTION

FIG. 1 is a front, right and top perspective view of a combined fan with light, showing our new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the combined fan with light of FIG. 1 shown in another configuration of use; and,

FIG. 10 is a rear, left and bottom perspective view of the combined fan with light of FIG. 9.

The dashed broken lines depict portions of the combined fan with light that form no part of the claimed design.

1 Claim, 10 Drawing Sheets
